UNITED STATES PATENT OFFICE.

WELCOME H. LAWSON, OF POUGHKEEPSIE, NEW YORK.

CENTRIFUGAL MACHINE.

996,776

Specification of Letters Patent.

Patented July 4, 1911.

Application filed May 27, 1910. Serial No. 563,734.

To all whom it may concern:

Be it known that I, WELCOME H. LAWSON, a citizen of the United States, and a resident of the town of Poughkeepsie, in the county of Dutchess and State of New York, have invented certain new and useful Improvements in Centrifugal Machines, of which the following is a specification.

My invention relates to centrifugal separating machines, and the object of my invention is to provide a novel means of driving the separator bowl and to provide means whereby said bowl may run in balance when rotating at a high rate of speed.

Referring to the drawings which form a part of this specification, Figure 1, shows a vertical sectional view of the driving shaft of a milk separator with the bowl mounted on its upper end and in its normal position when the bowl is not rotated. Fig. 2, is a similar view illustrating the bowl in the position that it usually takes when slightly out of balance and running at a high speed. Fig. 3, is a modified form in which the shaft is provided with two yielding springs, indicated in this case by rubber bands, and in which the shaft is provided, midway between said bands, with a circular projecting bead which serves as a fulcrum.

Referring to Fig. 1, A, indicates the separator bowl which is provided with a cone shaped opening A' in which opening is formed an annular groove A² in which is located a yielding spring B, which may be formed of rubber or other suitable yielding material.

Referring to Fig. 2, I have illustrated a separate casting D which is formed cone shape and carries the element B, to permit the element D to be removed and renewed when it becomes worn. C, indicates a vertical shaft which is driven by a suitable gear which co-operates with the worm thread C'. The lower end of the shaft C indicated by C² is located in a proper bearing and the shaft C is supported at a suitable point on its surface to prevent any lateral movement thereof. Heretofore it has been customary to provide means to allow the shaft C to move out of its vertical position to a predetermined degree to assist in balancing the bowl. My improvement consists in providing the bowl with the yielding spring material B through which the rotation of the shaft C imparts motion to the bowl A, and when the bowl A runs out of balance, it will

tend to swing to one side as illustrated in Fig. 2, until it finds its true center of rotation. I prefer to form a groove in the shaft C at C³ to increase the surface contact of the driving shaft with the material B and also assist in preventing the accidental displacement of said material.

Referring to Fig. 3, I have illustrated the element D as cylindrical in cross section and have shown a shaft D' provided with two grooves D² and D³ respectively, each of which is provided with a rubber spring B, and located on the shaft, preferably midway between the springs B, is a projecting bead D⁴ which contacts with the element D, and as the bowl E rotates and tends to find its center of gravity, the bowl rocks on the bead D⁴ as it slightly shifts its position relative to the shaft D', thereby bringing pressure to bear on the upper spring B on one side of the shaft D' and on the opposite side of the spring B the bead D⁴ acting as a fulcrum. By this means, the bowl E can rotate on the true axis of its mass and each of the spring rings B may be used to drive the same through frictional contact with the element D which is connected to the bowl E, either by friction or by any desired mechanical means.

In starting the machine, a certain relative movement will exist between the shaft C and bowl A until the inertia of the bowl is overcome and it comes to the same speed as the shaft C.

The bowl is supported on the upper end of the shaft at C⁴ as illustrated. The means illustrated are very simple and accomplish the object of my invention most successfully.

Having thus described my invention, what I claim as new and desire to secure is:

1. In a centrifugal separating machine, a bowl having a recess in its bottom located at the center thereof, a driving shaft, the upper end of which projects into said recess and supports said bowl, one of said elements being provided with an annular bead to serve as a fulcrum, and a ring of resilient material located above and below said annular bead in contact with said shaft and serving to drive said bowl.

2. In a centrifugal separating machine, a bowl having a recess in its bottom located at the center thereof, a removable element fitted in said recess and provided with a recess, a vertical shaft the upper end of which projects into said recess and carries said bowl;

12
said shaft having a projecting ring or bead which serves as a fulcrum, and a ring of resilient material located above and one below said fulcrum and serving as the medium through which said bowl is driven.

3. In a centrifugal separating machine, a bowl having a recess in its bottom located at the center thereof, a removable element fitted in said recess and provided with a recess, a vertical shaft the upper end of which projects into said recess and carries said bowl; said shaft having a projecting ring or bead which serves as a fulcrum, and having a groove located above and one below said fulcrum, a ring of resilient material located in each of said grooves and serving as the medium through which said bowl is driven.

4. In a centrifugal separating machine, a bowl having a recess in its bottom located at the center thereof, a removable element fitted loosely in said recess and provided with a recess, a vertical shaft the upper end of which projects into said recess and carries said bowl; said shaft having a projecting ring or bead which serves as a fulcrum, and

a ring of resilient material located above and one below said fulcrum and serving as the medium through which said bowl is driven.

5. In a centrifugal separating machine, a bowl having a recess in its bottom located at the center thereof, a removable element fitted in said recess and provided with a recess, a vertical shaft the upper end of which projects into said recess and carries said bowl; said shaft having a projecting ring or bead which serves as a fulcrum, and having a groove located above and one below said fulcrum at equal distances therefrom, a ring of resilient material located in each of said grooves and serving as the medium through which said bowl is driven.

Signed at New York city in the county of New York and State of New York this 10th day of December, A. D. 1909.

WELCOME H. LAWSON.
